UNITED STATES PATENT OFFICE.

JOSHUA TREAT, OF HAMPDEN, MAINE.

STAVE-JOINTING MACHINE.

SPECIFICATION forming part of Letters Patent No. 300,033, dated June 10, 1884.

Application filed May 24, 1883. (No model.)

To all whom it may concern:

Be it known that I, JOSHUA TREAT, of Hampden, in the county of Penobscot and State of Maine, have invented certain new and useful 5 Improvements in Stave-Jointing Machines; and I do hereby declare that the following is a full, clear, and exact description of the invention, that will enable others skilled in the art to which it appertains to make and use 10 the same, reference being had to the accompanying drawings, forming a part of this specification, in which—

Figure 1 shows an elevation of my invention; Fig. 2, a plan; Fig. 3, a section of table 15 and beveling devices through line *a b*, partial.

Same letters show like parts.

My invention consists of an improved machine for jointing staves, automatically graduating the bilge and list of staves varying in 20 width, and capable of adjustment in its various parts to staves of different patterns. It will be readily understood by reference to the annexed drawings, in which, at *a*, is shown the frame of the machine, provided with the 25 usual pulleys, shafting, &c. *b* shows the saw. Upon one side of this frame *a* is hinged a stave-supporting table, *c*; to the under side of which is attached a lever, *d*, pivoted rigidly upon a shaft, *e*, which projects upward through 30 the table *c*, and is provided above the surface of said table with a second lever, *f*. The other extremity of the lever *d* is attached by a short arm, *g*, to a lever, *h*, also turning on and with a shaft, *i*, projecting up through the surface 35 of the frame *a*, and having upon its upper end a lever, *j*, adapted to act against a spring-guide, *k*, as hereinafter described. The lever *d* is held outward by a spring, *l*, acting against its end *p*, and is provided at its end *m* with a 40 knob or projection moving, when the lever is turned on its pivot, over an inclined plane, *n*, and when at the highest portion of this plane supporting the table *c* in a level position. A spring, *o*, upon the upper side of the table *c* 45 presses down upon the stave, keeping it in position while being sawed, and, furthermore, insures the downward motion of said table upon its hinges when the knob *m* is moved from under it by the action of the lever *d*.

50 The operation of the machine is as follows: As the stave is pushed or fed toward the saw, it acts upon the lever *f*, throwing its end out-

ward, and turning the shaft to which is secured the lever *d*. This forces the end *p* of the lever *d* inward, carrying with it the arm *g* and lever *h*, and causes the lever *j*, secured to the shaft *i*, to act upon and force inward the end of the spring-guide *k*, the degree of curvature given to said guide, and consequently to the stave itself, being determined, as will be readily seen, by the width of the stave itself. As the end *p* of the lever *d* is thrown inward, its opposite end will be thrown outward in like proportion, and the knob *m* thereon, actuated by the weight of the table *c*, the stave, and the 65 downward pressure of the spring *o*, follows down the inclined plane *n*, before referred to, forming the list or bevel of the stave justly proportioned to its width. When the stave is sawed, the spring *l*, acting upon the end *p* 70 of the lever *d*, forces it with its attachments back into their former position, the table being brought to a level at the same time by the return of the knob to the higher part of the plane *n*, raising and holding the table. 75

In order to regulate the width of the strip to be removed from the stave, I attach the end *z* of my spring-guide to a sliding block or frame, *q*, one surface of which is inclined, as at *r*. This block and attached guide is adjustable by means of a screw-rod, *s*, and as it is moved longitudinally on the frame *c* the inclined surface, acting against said frame, forces the guide to or from the face of the saw.

All the important parts of my device, as 85 will be seen, are adjustably connected by slots and bolts, making it adaptable to staves of different patterns.

What I claim as my invention is—

1. In a stave-jointing machine, the combination of the hinged table *c*, pivoted arm *f*, adapted to be oscillated by the stave, the inclined plane *n*, secured to a fixed support, and the knob *m*, connected and oscillating with the arm *f*, and situated between said inclined plane 95 and the hinged table, substantially as set forth.

2. In a stave-jointing machine, the combination of the hinged table *c*, pivoted arm *f*, adapted to be oscillated by the stave, the inclined plane *n*, adjustable toward and from the 100 table on a fixed support, and the knob *m*, connected and oscillating with the arm *f*, and situated between said inclined plane and the hinged table, substantially as set forth.

3. In a stave-jointing machine, the combination of the hinged table *c*, pivoted arm *f*, adapted to be oscillated by the stave, the inclined plane *n*, attached to a fixed support, the lever *d*, connected and oscillating with the arm *f*, and adapted through the construction and connections shown to operate the spring-guide *k*, and the knob *m*, attached to said lever *d*, and situated between the hinged table *c* and the inclined plane, substantially as set forth.

4. In a stave-jointing machine, the combination of the hinged table *c*, for supporting the work, means for automatically raising said table to change the inclination of the work to the saw, and a presser adapted to hold the work against the table, and to insure the return of the latter when released by the raising devices, substantially as set forth.

5. In a stave-jointing machine, the combination of the hinged table *c*, for supporting the work, means for automatically raising said table to change the inclination of the work to the saw, and the spring *o*, attached to a fixed support, and adapted to hold the work against the table, and to insure the return of the latter when released by the raising devices, substantially as set forth.

6. In a stave-jointing machine, the combination of the main frame having a surface inclined to the plane of the saw, the wedge *q*, bearing against said surface and held in sliding contact therewith, the guide *k*, attached to said wedge in a position substantially parallel to the plane of the saw, and means for longitudinally adjusting said wedge to change the distance between the guide and the saw, substantially as set forth.

7. In a stave-jointing machine, the combination of the main frame having a surface inclined to the plane of the saw, the wedge *q*, bearing against said surface and held in sliding contact therewith, the guide *k*, attached to said wedge in a position substantially parallel to the plane of the saw, and a rod, *s*, extending to the end of the frame next to the operator for longitudinally adjusting said wedge, substantially as set forth.

In testimony that I claim the foregoing I have hereunto set my hand this 19th day of May, 1883.

JOSHUA TREAT.
